UNITED STATES PATENT OFFICE.

AARON SILVERSTEIN, OF NEW YORK, N. Y.

GARMENT.

Application filed November 9, 1920. Serial No. 422,619.

To all whom it may concern:

Be it known that I, AARON SILVERSTEIN, a citizen of the United States, and a resident of the city of New York, borough of 5 Manhattan, in the county and State of New York, have invented a new and Improved Garment, of which the following is a full, clear, and exact description.

This invention relates to a garment, and 10 has particular reference to a detachable vest for coats.

An object of the invention is to provide a vest for coats which may be readily applied to the inner face of a coat and can be 15 used as a vest when desired.

Another object of the invention resides in the provision of a vest of the character above described which can be applied to a coat with a minimum disturbance of the assembly 20 and construction of the coat proper, so that the fit of the coat is in no way affected by the application of the vest thereto, when used as a vest or otherwise.

A further object of the invention resides 25 in the provision of means whereby the ends of the vest, when not in use, may be slipped in back of the facing of the coat and be fastened therein so as to have the appearance of an ordinary coat lining, provision 30 being made that all fastening devices are hidden by the cloth of the coat.

A still further object resides in the particular construction and arrangement of 35 parts hereinafter described and claimed and shown in the accompanying drawings.

Hitherto in the construction of detachable vests for coats, it has been necessary to provide a particular arrangement of the facing of the coat, especially where it joins the 40 neckpiece in such a loose manner that the form of the coat as it fitted over the neck of the person wearing it readily got out of shape, thus destroying a line of beauty in the coat, which is one of the most essential 45 tail features of this garment. Furthermore, detachable vests hitherto used have been so applied to the body portion of the coat that when not in use their presence is apparent.

50 Also, the particular method of fastening vests hitherto employed has made it a laborious process, in most cases necessitating taking the coat off of the person of the wearer in order to hide the vest back of the facing or to take the vest out of the facing when used around the body of the wearer.

I aim to overcome these objections in the application of my vest to a coat by providing a coat in which the facing, particularly where it joins the neck portion of the coat, is firmly connected thereto in the usual manner so that the lines and curvature of the neck portion and the facing adjacent thereto are preserved at all times, whether the vest is being used or when it is not in use. 60 Furthermore, I provide means connected integrally with the body cloth of the coat whereby any and all fastening means are hidden.

The invention is illustrated in the drawings, of which—

Figure 1 represents the disposition of the vest when in use and shows the means within the facing of the coat whereby the facing may be held in place;

Figure 2 represents the disposition of the vest when it is not in use and the ends thereof are disposed back of the facing of the coat;

Figure 3 is a section taken through a part 60 of the garment.

Figure 4 is a diagram of a pattern illustration of the manner in which one portion of the coat to which the vest is attached is cut out; and

Figure 5 is a portion of the vest showing the disposition of the fastening means thereon.

In the drawings the invention is shown as applied to a coat having a lining portion 90 1, a facing 2 and a neck portion 3. The facing of the neck portion is joined along the line 4, shown in Figure 2, and the width of the facing at this portion, it will be observed, is unusually narrow. Below this 95 line 4 the facing portion 2 may be of any desired width, in accordance with whatever style of garment is being made. In Figure 2, it will be observed that the vest portion 5 is adapted to be adjustably fastened to 100 the coat by fastening means 6 beneath a portion of the lining thereof, particularly at the upper end of the vest. The rear lower face 7 of the vest 5 is connected by suitable fastening means 8 to similar fastening devices on a tab or lapel 9 which is formed along a seam 10 which is usually found in coats immediately beneath the armpit. The manner in which this tab or lapel 9 is formed will be later explained. This lapel has fastening means disposed on the inner side thereof so that when they engage the fasten-

ing means on the lower rear edge of the vest the fastening means are covered by the lapel 9.

The inner face of the vest 5 is lined with 5 the same material as the lining 1 of the coat. The outer edge of the vest is normally disposed back of the facing 2 and is connected thereto as shown by any suitable fasteners 11. When the vest is thus disposed not in use back of the facing 2, the 10 inner lining thereof being of the same material as the lining 1, the vest is not ordinarily observed as a separate garment.

It will be noted that where the upper 15 edge 12 of the vest is inserted underneath the adjacent edge of the facing 2 that this insertion can take place with a minimum disturbance of the facing, whereas in most vests of this sort the facing is, along the 20 edge 4, clasped or adjustably fastened to the neck portion 3 or the body of the coat and has to be unfastened in order to get the vest beneath the facing at this point. It is one of the essential features of this invention, 25 in that I can make a vest substantially flat and securely fasten it to the neckpiece so as to preserve the contour of the coat, and insert the vest beneath the facing and remove it from beneath the facing with a minimum 30 disturbance thereof. It will be observed also that the upper end of the vest is fastened to the coat as near as possible to the neckpiece so that, as shown in Figure 1, when the vest is in use, wrapped around 35 the body of the wearer, the line 12 of the vest extends with the proper curvature around the neck of the wearer.

The type of fastening means used is not particularly material, although snap fasteners have been shown in the various places 40 where fasteners are needed.

In Figure 4, the opening 13 in the patterns 14 is cut in the usual manner. However, in order to provide the tab 9 which I show in this figure, I allow a corresponding width 15 at the upper right hand edge of the pattern, and also a corresponding width 16 at the lower right-hand edge of the garment, so that I can sew the edge 17 to the edge 18, shown in dotted line in Figure 4, 45 and the intervening space between the edge 18 and the edge 19 will form a lapel 9. This can be achieved by folding an original pattern along a line 20, shown in Figure 4, and then remarking this disturbed pattern on 50 to a new sheet, giving as a result the pattern shown in Figure 4.

It will thus be observed that I have provided a vest which can be simply and readily applied for use and stored away 55 within the facing of the coat when not in use, and which can also be completely detached from the coat, if desired. This vest portion simulates the ordinary lining of the coat when not in use, and all fastening 60 means are hidden. Moreover, it can be readily attached to a coat portion which has been provided with a firm and secure connection between the upper end of the facing and the collar portion, whereby all the 65 proper and desired curves are maintained.

What I claim is:

The combination with a coat having a facing, of a vest adapted when not in use to be disposed beneath the facing, fastening 70 means on the coat and one end of the vest adapted to co-operate to join the vest and coat together, and an integral tab or lapel 75 on the coat adapted to cover the fastening means on the coat and the vest.

AARON SILVERSTEIN.
